UNITED STATES PATENT OFFICE.

CHARLES T. SHAFER, OF SPRINGFIELD, OHIO.

FOUNTAIN PEN-HOLDER.

SPECIFICATION forming part of Letters Patent No. 279,025, dated June 5, 1883.

Application filed January 24, 1883. (No model.)

To all whom it may concern:

Be it known that I, CHARLES T. SHAFER, of Springfield, in the county of Clarke and State of Ohio, have invented a new and useful Improvement in Fountain Pen-Holders; and I do hereby declare that the following is a full, clear, and exact description of the same.

Fountain pens and holders, or pens in which the holder is made the receptacle for carrying the supply of ink, are in common use, and I do not propose to claim, broadly, such a holder.

With my invention any kind of a pen—steel, gold, or otherwise—can be used, and any fluid ink can be used, and the flow of ink regulated at will without the use of spirals, sieves, or springs.

That others may fully understand my invention, I will particularly describe it, reference being had to the accompanying drawings, 20 wherein—

Figure 1 is an elevation, parts of the holder being in longitudinal section. Fig. 2 is an elevation of the barrel detached. Figs. 3 and 4 are parts detached. Fig. 5 is a longitudinal 25 section of the pen end; Fig. 6, the loose weight to be inclosed.

C is the barrel or tube constituting the ink-holder of the pen. The top is open, and provided with thread and screw plug or top A 30 to make an air-tight stopper. It also has a small hole or port, P, at bottom, or side near the bottom, for the discharge of ink to the pen. D is a tube fitting closely over tube C up to point G, having also a small hole or port, P', 35 at bottom of tube, or near the bottom, corresponding in position with the port P. E is a tight-fitting sleeve, open at both ends, and used to slip over D to receive and hold the pen. B is a loose or free weight, having a specific gravity greater than that of the ink, inclosed within 40 the ink-barrel C. These parts A, B, C, D, and E can be made of any desired material or shape suitable for the purpose.

The method of using my invention is as follows: The weight B is put in the tube C. The tube D is then fitted over the tube C, and so placed that the holes P and P' do not register with each other. The tube C is filled with ink and the plug A is screwed into top of said 45 tube. The pen-holder E and pen F being adjusted on the tube D in such position that the hole P is opposite the median line of the pen, said tube D is turned so that the holes P and

P' are opposite each other, and the ink may flow through said holes and charge the pen. Small 55 notches G-H or other suitable means—one on tube C and one on tube D—indicate when said holes or ports are in or out of register. The pen is then ready for use. A quick vertical or oscillatory motion of the hand causes the weight 60 B to act as a plunger with sufficient force to drive a drop of ink through the ports P P' and down to the point of the pen. This plunger effect is independent of the quantity of ink in the reservoir, and by it the last drop may be 65 driven out. This operation may be repeated as often as may be necessary to cause a steady supply of ink.

I am aware that a fountain pen-holder has been provided with a close-fitting float or piston of less specific gravity than the ink, to maintain a separation between the ink and the open air-space in the top of the holder. That is essentially different from my invention, because, first, I do not admit air at the top of my 70 reservoir as ink is discharged to the pen, and therefore I have no need for a floating separator; second, it is manifest that a float having less specific gravity than the ink cannot add to the plunger action of the column of ink itself 75 when the pen is shaken up and down, whereas my weight, being indefinitely heavier than the ink, will act as a plunger independent of the ink.

Having described my invention, what I claim 80 as new is—

1. In a fountain pen-holder, the combination, with the pen section and barrel or reservoir provided with a port through which ink may be driven to the pen, of a loose plunger 85 or weight of greater specific gravity than the ink, whereby the ink may be driven through said port when the pen is shaken up and down.

2. The combination, in a fountain pen-holder, of a barrel, C, having a port, P, a sleeve, D, fitted thereto, and provided with a corresponding port, P', means whereby an ordinary writing-pen may be attached to said holder, and a loose plunger-weight, B, inclosed within 90 said barrel, for the purpose set forth.

CHAS. T. SHAFER.
